UNITED STATES PATENT OFFICE

2,602,200

VENTILATED METAL AWNING

Carson A. Alcorn, Grand Island, Nebr.

Application April 26, 1949, Serial No. 89,665

1 Claim. (Cl. 20—57.5)

1

This invention comprises novel and useful improvements in a ventilated metal awning and more specifically pertains to a sheet metal awning of durable but light and economical construction which may be readily mounted or dismantled for storage.

The primary object of this invention is to provide a metal awning for windows and the like which shall be of light weight economical construction, easily assembled or dismantled, which may be compactly stored, and which shall be of a ventilated construction.

A further object of the invention is to provide a metal awning in accordance with the preceding object which is capable of being assembled or erected in a variety of manners and positions with respect to a window frame.

These, together with various ancillary features and objects of the invention which will later become apparent as the following description proceeds, are attained by the present invention, preferred embodiments of which have been illustrated by way of example only in the accompanying drawings, wherein:

Figure 1 is a perspective view, parts being broken away, of one embodiment of the invention showing the same assembled according to one manner of its usage;

Figure 2 is a side elevational view of the embodiment of Figure 1, when showing the awning assembled in an alternative position or manner of attachment;

Figure 3 is a vertical sectional view through the awning as assembled in Figure 1, a fastening member of the awning being indicated in an alternative position in dotted lines to illustrate its pivotal movement;

Figure 4 is a vertical transverse sectional view taken substantially upon the plane of section line 4—4 of Figure 3 and illustrating the mounting frame work of the awning;

Figure 5 is a perspective view similar to Figure 1 showing a second and simpler embodiment of the invention;

Figure 6 is a fragmentary vertical transverse sectional view taken substantially on the plane indicated by the section line 6—6 of Figure 5 and showing in particular the manner of mounting this embodiment of the invention upon a window frame; and

Figure 7 is a vertical longitudinal sectional view taken substantially upon the plane of section line 7—7 of Figure 5.

Referring first to the preferred embodiment of the invention which is illustrated in Figures 1—4, it will be seen that numeral 10 designates any suitable vertical supporting surface upon which the awning may be mounted, such as for example as a window frame or the like, and to which this embodiment is intended to be firmly secured in

2

either a rigidly fixed position as shown in Figure 1 or in a somewhat elevated position as shown in Figure 2.

The awning itself includes a pair of side panels 12 formed preferably of sheet metal such as aluminum or the like, and which are shaped in the form of right triangles, which are disposed with their perpendicular edges forming respectively inturned flanges 14 and 15 at their rear and lower edges, the other side edge of the triangle being either a plain edge or seamed or folded upon itself if desired. The awning further includes a roof panel preferably composed of a single sheet of material although the same could be made up of a number of separate panels rigidly attached together in known manner if desired, this roof panel being indicated by the numeral 16, and being provided at its upper and bottom edges with downwardly turned integral flanges 18 and 20, which respectively form means for mounting or supporting the awning and for providing a valance at the lower edge thereof, the roof panel being further provided with lateral downwardly turned flanges 22.

It is intended that the triangular side panels may be detachably but rigidly secured to the roof panel 16 as by suitable rivets or the like 24, see Figure 3, and also Figure 2, which extend through the flanges 22 and the upper inclined edge of the triangular side panels 12. Preferably the triangular members are disposed on the inner surface of the lateral flanges 22, so as to better prevent the ingress of rain or the like to the interior or the awning to the joint formed by the side panels 12 and the lateral flanges 22.

As will be further apparent from Figure 3, the top down-turned flange 18 of the roof panel 16 is disposed between the upper portions of the rear inturned flanges 14 of the side panels 12, so that the latter will assist in holding the roof panels against the supporting surface.

The top downwardly turned flange 18 has attached thereto a hinge member 26, a new suitable member of these hinges being provided whereby the entire awning may be directly and hingedly connected to the vertical supporting surface 10 so that the awning may be raised or lowered as desired. In its lowered movement, the awning assumes the position shown in Figure 1, and is rigidly retained in its lowered position by fastening means which may conveniently comprise I-bolts 28 secured to the vertical surface 10 and extending through vertically elongated slots 30 formed in the rear flanges 14, whereby the I-bolts may be rotated after their insertion in these slots to retain the awning in its lowered position.

The upper portions of the triangular panels 12, and of the lateral flanges 22, are perforate,

as by providing a plurality of apertures 32 extending therethrough, whereby heated air trapped beneath the upper inclined surface of the awning may readily escape thus cooling the space beneath the awning by permitting a circulation of air.

As shown more clearly in Figure 1, the roof panel 16 may be provided with appropriately positioned web-like ridges 34, which serve to reinforce and strengthen and add rigidity to the thin sheet metal of which the awning is formed.

As so far described, it will be seen that the awning may be attached as shown in Figure 1 rigidly to a window frame or the like, and thus form a sharply sloping awning preventing the access of rain or snow to the upper part of the window, and shuttering the window space.

However, the assembly above described may also be alternatively positioned for a modified use. For this purpose, an extension member which may conveniently take the form of an L-shaped or angle iron member 36 is terminally pivoted as at 38 by a rivet or the like, to the lower inturned edge of the side panel 12 and at its other end is attachably secured as by a wing bolt 40 to the lower end of the lateral flange 22, whereby it may form a stiffening or reinforcing member as shown in full lines in Figure 3, when the awning is assembled in the manner shown in Figure 1.

However, the bolt 40 may be removed, the extension 36 may be pivoted about its pin 38, and the other end of the extension may be secured by the above mentioned wing bolt 40 to an I-bolt 42 appropriately positioned upon the surface 10, so that the entire awning assembly will be raised about its hinge 26 into the position shown in Figure 2. As will be seen, in this position the lowermost edge of the awning is raised higher, so that more light and air may be admitted to the window opening, while the window space is still protected by the awning roof from the direct effect of the sun's rays, from rain, snow or the like.

Attention is next directed to Figures 5-7 which show a much simplified construction of awning which embodies some of the features of the invention, but which is intended to be detachably, rigidly but non-adjustably mounted upon a window opening. In this embodiment, the window opening 10 or other vertical supporting surface has rigidly attached thereto a pair of triangular side panels 112 which may be identical with the side panels 12 of the preceding embodiment, including vertically and horizontally disposed rear inwardly turned flanges 114 and upwardly turned flanges 116 at their lower ends, the upper edges of these side panels being secured as by bolts, rivets or the like 118, to the downwardly turned lateral flanges 120 integrally formed upon the roof panel 122. This roof panel is provided with an integral downwardly turned bottom edge flange 128 together with a downwardly turned upper edge flange 126, the latter being mounted over the upper ends of the flanges 114 and between the flanges 114 and the vertical supporting surface 10. One or more reinforcing members in the form of angle iron members 128 are secured to the under surface of the roof panel 122 as by rivets or bolts 130, and are terminally secured to the lateral flanges 120.

It should be here noted that this reinforcing means may also be employed in the roof panel construction of the preceding embodiment.

As in the preceding embodiment the upper portions of the side panels 112 and of the lateral flanges 120 may be perforated or apertured as at 132 for the purpose of ventilation, and escape of heated air from beneath the awning.

Also as in the preceding embodiment, the rear flanges 114 may be provided with elongated key hole type of slots 134 for detachably engaging fastening screws 136 carried by the vertical supporting surface 10, these screws cooperating with clamping brackets 138 suitably secured as at supporting surface 10 and adapted to overlap the flanges 114 or 126 whereby the entire awning assembly may be detachably but rigidly secured to the supporting surface 10.

From the foregoing, the construction and functioning of the device will be readily understood and further explanation is believed to be unnecessary. However, since numerous modifications and equivalents will readily occur to those skilled in the art after the consideration of the foregoing specification and accompanying drawings, it is not desired to limit the invention to the exact construction as shown and described. Accordingly, all suitable modifications and equivalents may be resorted to, falling within the scope of the appended claim.

Having described the invention, what is claimed as new is:

A sheet metal awning comprising a roof panel having lateral downwardly turned flanges and depending top and bottom end flange, triangular side panels having perpendicularly disposed in-turned flanges on their rear and lower edges, said side panels being secured on their upper edges to the lateral flanges of the roof panel, said side panels and said lateral flanges being perforate at their uppermost portions to afford escape for heated air trapped beneath the awning, said top flange and said rear inturned flanges being secured to a vertical supporting surface, said side panels bearing an extension member terminally pivoted to the rear end of the lower inturned flanges and means for selectively securing the other end of the extension member to the front end of said lower inturned flange to form a reinforcing member or to said vertical supporting surface to hold the awning in an elevated position.
